BUTTON LOOP

Filed Aug. 21, 1930

UNITED STATES PATENT OFFICE

GEORGE B. HEATHER, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed August 21, 1930. Serial No. 476,786.

This invention relates to button loops particularly adapted for use on garment straps, the loop being specially adapted to be suspended at the end of a strap loop in readiness to be clipped over a button the shank of which may be urged from a button-receiving loop into a smaller retaining loop from which it cannot be unintentionally withdrawn.

The objects of the invention are to provide by bending a piece of resilient wire, a reversible button loop of which the wire ends are arranged in the plane of the loop and provided with an interlocking means, independently of any enclosing clip member, limiting the relative outward movement of said ends in said plane; and to provide such a button loop with means for securing the wire ends against relative movement out of the plane of the loop. With these and other objects in view, as may become apparent from the within disclosures, the invention consists not only of the particular form herein pointed out and in the drawing illustrated, but readily admits of certain modifications within the scope of what hereinafter may be claimed.

The character of the invention may be best understood by reference to one illustrative device embodying the invention and illustrated by the accompanying drawing in which the Figure 1 is an upright elevation of the device in normal condition, a reversed elevation of which would be identical therewith; the Figure 2 is an upright elevation of the device in expanded condition; and the Figure 3 is a side elevation of the device illustrating a clip mounted thereon.

The device is preferably made from a piece of resilient wire of which a middle portion is bent to provide the suspension loop 1 and the spring arms 2 and 3 depending therefrom to provide the axially associated loops 4 and 5 having an intermediate normally contracted throat 6. The wire end portions 7 and 8 are arranged horizontally parallel in spaced relation in the plane of the loop, the portion 7 being bent, as at 9, to off-set the portion 7 within the loop 5, each wire end portion 7 and 8 being provided with a shoulder 10 adjacent the wire extremity, the shoulders 10

being preferably formed by axially bending the extremity of the wire end portion 7 away from the throat 6, and by axially bending the extremity of the wire end portion 8 toward the throat 6, the bent extremities providing 55 the interengageable shoulders 10 in the plane of the button loop, as illustrated by the Figures 1 and 2. The shank S of a button with in the loop 4, as illustrated by the Figure 1, 60 may be manually urged into the throat 6 by expanding the button loop as illustrated by the Figure 2, the expanding of the loop causing the wire end portions 7 and 8 to relatively slide along the plane of the loop, the 65 expansion of the loop being limited by the interlocking engagement of the shoulders 10, as illustrated by the Figure 2. The clip member 11 encloses the wire end portions 7 and 8 and secures them against relative movement 70 out of the plane of the loop as illustrated by the Figure 3.

I claim:

A reversible button loop comprising a piece of resilient wire of which a middle portion is bent to form a suspension loop, the 75 remaining portions cooperating to form associated loops in axial alignment and having an intermediate normally contracted throat, one arm being off-set in the plane of the loops within the adjacent loop and having its extremity bent axially away from said throat, and the other arm being bent into spaced parallel relation with, and overlapping in said plane, the off-set arm and having its extremity bent axially toward said throat, the bent 80 extremities providing interengaging shoulders in said plane to limit the relative expanding movement of said arms in said plane, and a clip member securing the parallel arm portions against relative movement out of said 85 plane.

GEORGE B. HEATHER.
